ATTORNEY

UNITED STATES PATENT OFFICE

161,772

MULTIPLE STUDY UNIT OR THE LIKE

Angus Snead Macdonald, near Rapidan, Va.

Application September 9, 1949, Serial No. 4,920

Term of patent 14 years

(Cl. D33—11)

To all whom it may concern:

Be it known that I, Angus Snead Macdonald, a citizen of the United States, residing near Rapidan, in the county of Orange and State of Virginia, have invented a new, original, and ornamental Design for Multiple Study Units or the like, of which the following is a specification, reference being had to the accompanying drawing, forming a part thereof.

In the accompanying drawing:

Fig. 1 is a top plan view of a multiple study unit, showing my new design;

Fig. 2 is a perspective view thereof.

I claim:

The ornamental design for a multiple study unit or the like, substantially as shown.

ANGUS SNEAD MACDONALD.
